UNITED STATES PATENT OFFICE.

CHARLES W. HOWELL, OF NEWARK, NEW JERSEY, ASSIGNOR TO SUN TYPEWRITER COMPANY, A CORPORATION OF NEW JERSEY.

TYPE-WRITING MACHINE.

No. 923,527.

Specification of Letters Patent.

Patented June 1, 1909.

Application filed December 10, 1906. Serial No. 347,202.

To all whom it may concern:

Be it known that I, CHARLES W. HOWELL, a citizen of the United States, residing in Newark, in the county of Essex and State of New Jersey, have invented certain new and useful Improvements in Type-Writing Machines, of which the following is a specification.

This invention relates to writing machines in which keys are depressed to effect type impressions upon the paper, and in which the carriage is fed a letter space at each key depression; and particularly to those machines in which means are provided for preventing the types from printing when the end of a line of writing is at hand.

One of the objects of the invention is to provide simple, inexpensive and reliable means controlled by the letter feeding carriage for preventing the types from printing, at the end of the line, and to provide a simple device for releasing the types to enable a word to be completed, and also to provide a simple reliable margin gage mechanism including right hand and left hand carriage stops both releasable by the same device that releases the types. I illustrate these improvements embodied in a "Sun" typewriting machine in which a universal bar operated by all the type bars is pivoted upon a pair of rock arms; and I provide interponents which are movable by the carriage to positions between said rock arms and fixed abutments provided upon the framework, thereby preventing vibration of the arms and preventing the types from reaching the platen. The carriage is provided with a tappet adjustable to lock the types at a variable point in the line of the writing; and said tappets are releasable by means of a key which is also adapted to release the carriage from the control of adjustable stops, which regulate the right and left hand margins upon the paper. Other features of my improvements relate to paper-feeding devices comprising front and rear rolls pressing against the under side of the platen and releasable by simple and effective means, and also including releasable front paper-guiding fingers of novel construction and operation.

My improvements further include a novel line-space regulator and also a platen releasing mechanism having novel features.

In the accompanying drawings, Figure 1 is a sectional elevation taken from front to rear

of a "Sun" typewriting machine showing my improvements applied thereto. Fig. 2 is a front elevation partly in section of the line locking mechanism, seen at Fig. 1. Fig. 3 is a plan of a fragment of a release key rod 60 showing its loose connection to a crank, seen at Fig. 2. Fig. 4 is a plan of an interponent showing its loose-mounting upon an endwise movable rock shaft, the latter having a pin for effecting movement of the interponent 65 lengthwise of the shaft. Fig. 5 is a plan of the mechanism seen at Fig. 1.

Keys 1 are mounted upon bell-cranks 2 connected by links 3 to type bars 4 which swing upwardly and rearwardly to strike 79 against the front side of a platen 5. The latter is mounted in a frame which comprises a truck 6 and end pieces 7, 8 erected thereon; said truck being held by balls 9 upon front and rear tracks 10, 11. In said 75 machine, the tracks and platen frame are lifted up and down bodily to enable different types to print. The platen frame or carriage is driven by a spring, not shown, and provided with a letter spacing mechanism including a universal bar 12 operable by all the type bars; said universal bar being segmental and overlying a slotted segment 13, in which the type bars are held by means of a curved pivot rod 14. 85

Upon the rear side or edge of the truck 6 is fastened a bar 15 having teeth 16 cut in its top face at letter space intervals. Adjustable along said bar is a stop member 17 for regulating the right hand margin on the 90 paper sheet. This stop member is made of sheet metal and comprises a plate which overlies the teeth 16 and ears 18 bent down alongside of the rack bar and turned into recesses or grooves 19 formed in the base of 95 the bar, so that the stop member is securely held against turning upon or lifting off from the bar.

Screws 20 and 21 pass down through a lever 22, the latter having a tooth 23 projecting down through a hole 24 in the stop member 17 and taking into one of the rack teeth or notches 16. At its other end, the lever is provided with a finger-piece 25, whereby the lever may be rocked to lift the 100 tooth 23 out of the notches 16, and also whereby the stop member 17 may be slid along the rack bar. A spring 26 is coiled 105 around the screw 21 to press the tooth 23 down, and the head of the screw 20 is suffi- 110

ciently high above the lever to permit the necessary play of the latter, as seen at Fig. 2. Extending rearwardly from the stop member 17 is a stop 27; and in the path of the latter is an abutment 28 to coöperate with the stop 27 to arrest the movement of the carriage in letter feeding direction. Said abutment is carried upon the upper end of an arm 29, which is hinged at 30 upon a pair of ears 31 secured upon the framework, that is upon the vertical shifting frame 32 that carries the carriage tracks 10, 11. The abutment is mounted upon the hinge 30, so that it may be swung rearwardly out of the path of the stop 27. To effect the release of the stop, a key 33 is provided near the keyboard upon the front end of a rod 34 extending to the rear of the machine and provided with an elbow 35 having a slot 36 to engage a pin 37 upon an arm 38, which is rigidly connected to and swings with the abutment arm 29. By pressing back the key 33, the abutment 28 is swung back far enough to clear the stop 27 and release the carriage for further letter feeding movement. A spring 39 on the rod 34 returns the latter and the abutment to normal positions upon the release of the key. The carriage may then advance until arrested by the engagement of a stop 40 with an abutment 41 fixed upon the framework, said stop 40 being fixed upon the carriage and determining the final limit of movement of the carriage in that direction.

An arm 42 is bent down from the front side of the stop member 17 and formed with a forwardly projecting tappet 43. In the path of said tappet is an upstanding arm 44 fixed upon a horizontal rock shaft 45 journaled in brackets 46 fixed upon the framework of the machine. Said shaft is movable endwise by the action of the tappet 43 upon the projection 44. Hanging from said rock shaft are two arms 47 carrying interponents 48 which normally occupy positions alongside of the rock arms 49 hinged at 50 upon the framework, and also hinged at 51 to the universal bar 12; said rock arms 49 vibrating at every type stroke and forming part of the carriage feeding mechanism. The rock shaft 45 has pins 52 projecting through slots 53 in the interponent arms, so that when the shaft is moved endwise by the tappet 43, the interponents 48 are moved to the left at Fig. 2 into positions directly back of the vibrating arms 49, and between the same and fixed abutments 54 provided upon the framework. The interponents rest against the abutments so that the movement of the vibrating arms 49 is blocked, and the types are prevented from reaching the platen.

If now it is desired to write a few more letters, so as to complete a word, the key 33 is pressed back together with the rod 34, and a

slotted arm 55 on the latter swings back a crank 56 depending from the end of the rock shaft 45, whereby the latter is rocked and the projection 44 is swung forward, to escape the tappet 43; whereupon a compression spring 57 upon the rock shaft forces the latter to the right, at Fig. 2, to normal position, thus withdrawing the interponents 48 and permitting the arms 49 and the universal bar 12 to operate and the types to print. Upon the release of the key 33, the spring 39 moves the rod 34 forwardly, thereby rocking the shaft 45 back to normal position. The type keys may then be operated to add a few characters upon the end of the line of writing. The rear edge of the tappet 43 is beveled, and the corresponding portion of the projection 44 may also be beveled, as seen at Fig. 5, to enable the projection to ride freely over the tappet when the carriage is drawn back to begin a new line of writing; the tappet camming the projection forwardly against the tension of the spring 39 which subsequently restores the parts to normal positions.

The margin on the right hand edge of the paper is regulated by a stop member 58 having a stop 59 to engage the opposite side of the abutment 28; the member 58 being substantially similar to the member 17 and having a corresponding tooth lever 60, to engage the rack 16, whereby the width of the margin may be regulated. If it is desired to write in the margin, it is only necessary to press back the key 33 and move the abutment 28 back out of the way of the stop 59, whereupon the carriage may be moved to the right, as far as desired. The stops 27 and 59 are rounded at 27^a and 59^a upon their outer edges, so as to cam the abutment 28 out of the way when necessary. The carriage is also provided with a stop 61, to engage the fixed stop 41 to determine the final limit of return movement of the carriage.

The slot 36 in the release rod 35 may be sufficiently high to accommodate the up and down shifting movements of the frame 32.

Having thus described my invention, I claim:

1. In a typewriting machine having a set of key-operated types and a carriage and also including a member reciprocating at each type stroke, the combination of a tappet adjustable along the carriage, a rod extending along the carriage and mounted upon the framework of the machine and carrying an arm in the path of said tappet, an abutment, an interponent upon said rod, and movable thereby into position to coöperate with said abutment to arrest said reciprocating member to prevent the types from printing, and means for turning said rod independently of the said interponent to rock said arm, out of path of said tappet.

2. In a typewriting machine having a set of key-operated types and a carriage and a

also including a universal bar and a pair of arms connected to the universal bar and reciprocating at each type stroke, the combination of a tappet adjustable along the carriage, a rod extending along the carriage and mounted upon the framework of the machine and carrying an arm projecting into the path of said tappet, a pair of abutments, interponents movable by an endwise movement of said rod into positions to coöperate with said abutments to arrest said reciprocating arms to prevent the types from printing, means for turning said rod independently of said interponents to rock said projecting arm out of the path of said tappet, and means for returning said interponents and said rod to normal positions.

3. In a typewriting machine having a set of key-operated types and a carriage and also including a member reciprocating at each type stroke, the combination of a tappet adjustable along the carriage, a rod extending along the carriage and mounted upon the framework of the machine and carrying an arm in the path of said tappet, an abutment, an interponent upon said rod and movable thereby into position to coöperate with the abutment to arrest said reciprocating member to prevent the types from printing, and means for turning said rod independently of said interponent to rock said arm out of the path of said tappet; said arm and tappet having relatively inclined surfaces engaging each other upon the return of the carriage, to permit the arm to ride freely past the tappet.

4. In a typewriting machine having a set of key-operated types and a carriage and also including a member reciprocating at each type stroke, the combination of a stop member adjustable along the carriage, a movable abutment upon the framework of the machine in the path of said stop member to coöperate therewith to arrest the carriage, a tappet upon said stop member, a rod extending along the carriage and mounted for both endwise movement and rotative upon the framework of the machine and carrying an arm projecting into the path of said tappet, an abutment, an interponent caused by the endwise movement of said rod to move into the path of said reciprocating member and coöperate with said abutment to prevent the types from printing, a finger piece having means to turn said rod to rock said projecting arm out of the path of said tappet, resilient means for returning the interponent and the rod to normal positions when released by said finger piece, and means for enabling said finger piece to move said abutment out of the path of said member.

5. In a typewriting machine having a set of key-operated types and a carriage and also including a member reciprocating at each type stroke, the combination of a stop

member adjustable along the carriage, a movable abutment upon the framework of the machine in the path of said stop member to coöperate therewith to arrest the carriage, a tappet upon said stop member, a rod extending along the carriage and mounted for both endwise movement and rotation upon the framework of the machine and carrying an arm projecting into the path of said tappet, an abutment, an interponent caused by the endwise movement of said rod to move into the path of said reciprocating member and coöperate with said abutment to prevent the types from printing, a finger piece having means to turn said rod to rock said projecting arm out of the path of said tappet, resilient means for returning the interponent and the rod to normal positions when released by said finger piece, means for enabling said finger piece to move said abutment out of the path of said member, an additional abutment mounted upon the framework, and an additional stop upon the carriage to engage the additional abutment to determine the final limit of movement of the carriage.

6. In a typewriting machine having a letter-feeding carriage and a set of types, the combination of a rack for said carriage, a stop member adjustable along said rack, an abutment hinged upon the framework in the path of said stop member, to coöperate therewith to arrest the carriage when returning to begin a new line of writing, a second stop member also adjustable along said rack and engageable with the opposite side of said hinged abutment to arrest the carriage movement in letter-spacing direction, a spring-pressed release-rod loosely connected to said hinged abutment and extending to the front of the machine, to swing the abutment out of the path of the stops, additional abutments fixed upon the framework, additional stops projecting from the ends of the carriage to engage said additional abutments to determine the final limits of the movements of the carriage, a tappet upon the second stop member, an endwise movable rock-shaft carrying an arm projecting into the path of said tappet, a pair of interponents movable by means of an endwise movement of said rock-shaft into positions between a pair of fixed abutments on the framework and a pair of arms connected to a universal bar, to coöperate with said abutments and said arms to prevent the types from printing, an arm upon said rock-shaft and connected to said release-rod to enable the latter to release said projecting arm, a spring for returning said shaft endwise to normal position to withdraw said interponents when said projecting arm is released from said tappet; said projecting arm having a beveled edge to ride over said arm to rock said shaft idly during the return of the carriage, and said interpo-

4
nents having loose connections to said shaft so that the latter may rock independently of said interponents, and a spring for returning said release-rod and hinged abutment to normal position.

7. In a typewriting machine having a letter-spacing carriage and a set of types, the combination of a tappet upon the carriage, a rock-shaft carrying an arm in the path of said tappet, a pair of interponents carried loosely upon said shaft and movable thereby into positions between a pair of fixed abutments on the framework and a pair of arms carrying a universal bar, to coöperate with said abutments and said arms to prevent the types from printing, means to release said arm from said tappet, and a spring for returning said shaft endwise to normal position to withdraw said interponents when said arm is released.

8. In a typewriting machine having a letter-feeding carriage and a set of types, the combination of a rack for said carriage, a stop member adjustable along said rack, an abutment hinged upon the framework in the path of said stop member, to coöperate there-

with to arrest the carriage, a spring-pressed release-rod loosely connected to said hinged abutment and extending to the front of the machine, a tappet upon the stop member, an endwise movable rock-shaft carrying an arm projecting into the path of said tappet, an interponent movable by means of an endwise movement of said rock-shaft into positions between a fixed abutment on the framework and an arm connected to a universal bar, to coöperate with said abutment and said arm to prevent the types from printing, a crank upon said rock-shaft, an arm upon said release-rod to enable the latter to turn said shaft to release it from said tappet, and a spring for returning said shaft endwise to normal position to withdraw said interponents when said projecting arm is released from said tappet.

In testimony whereof, I have hereunto set my hand, this 6th day of December, 1907.

CHARLES W. HOWELL.
